Patented Aug. 26, 1919.

UNITED STATES PATENT OFFICE.

HORACE M. SHEEKS AND FRED W. STEIN, OF ATCHISON, KANSAS.

ELECTROTHERAPEUTICAL APPARATUS.

1,313,957.

Specification of Letters Patent. Patented Aug. 26, 1919.

Application filed March 23, 1917. Serial No. 157,013.

To all whom it may concern:

Be it known that we, HORACE M. SHEEKS and FRED W. STEIN, citizens of the United States, residing at Atchison, in the county of Atchison and State of Kansas, have invented certain new and useful Improvements in Electrotherapeutical Apparatus, of which the following is a specification.

This invention relates to electro-therapeutical apparatus for producing electrical currents which are particularly beneficial in the treatment of diseases due to the lack of blood circulation and insufficient nerve stimulation.

To this end the invention contemplates a novel and improved electrical translating instrument from which a mild low voltage, low amperage and true sinusoidal current can be obtained for the purposes above referred to, and which may be conveniently handled and used in a thoroughly safe and effective manner.

Another object of the invention is to provide a device which may be readily used in connection with a conventional lamp socket of a house lighting circuit, without removing the shade or globe, where one is used, or in any way altering the wiring connections or other parts of the fixture. In this connection, the invention aims to provide a device which may be quickly made ready for use and likewise removed and stored away, and which when in service permits of the usual incandescent lamp being used for lighting purposes, thereby not depriving the patient of a light when only one lamp socket is available from which to tap the current.

A further object of the invention is to provide a device which is susceptible of a neat and attractive embodiment, and of a more or less ornamental appearance, thereby materially enhancing its commercial aspect. In this latter connection it is proposed to provide a device which is strong and durable in construction, and reliable and positive in action, and therefore of maximum service and efficiency. Furthermore, the invention also proposes to provide substantial means for connecting the applicator cords therewith, whereby interruption in the flow of the applied current is eliminated.

With the above and other objects in view which will more readily appear as the nature of the invention is better understood, the same consists in the novel construction, combination and arrangement of parts,

hereinafter more fully described, illustrated and claimed.

A preferred and practical embodiment of the invention is shown in the accompanying drawings, in which—

Figure 1 is a view showing the application of the invention.

Fig. 2 is an elevation thereof.

Fig. 3 is a longitudinal sectional view. 65

Fig. 4 is also a longitudinal sectional view partly in elevation, and taken at right angles to the section of Fig. 3.

Fig. 5 is a detail cross-sectional view on the line 5—5 of Fig. 2. 70

Fig. 6 is a diagrammatic view, showing the electrical circuits.

Similar references designate corresponding parts throughout the several figures of the drawings. 75

In carrying the present invention into effect, it is proposed, as previously pointed out, to provide a device which is substantial and durable, and not susceptible of becoming readily broken or damaged through the usual handling, thereby rendering it always ready for service by the simple act of screwing the same into a conventional lamp socket. As will be observed from Fig. 1, the present device is designated generally as D, and is so constructed that it may be readily screwed into the lamp socket S of the house lighting system, while the lamp L, removed from the socket, may be screwed into the opposite end thereof, to thereby not only become a part of the circuit in which the device D is included, but to also give off light in the usual manner.

For the purpose of utilizing the benefit of the electrical current passing through the device D, the same is preferably provided with suitable means, which will hereinafter be more fully referred to, for coupling thereto the applicator cords C. These cords may be of any desired length, and are preferably provided at each end with the coil-spring attaching members E, for respectively connecting with a part of the device D and the hand grips H, or their equivalent. In this latter connection, it will of course be understood that in place of the hand grips H, there may be utilized other body contact devices well known to the art.

Referring now more particularly to the novel construction of the device D, it will be observed that the same includes in its organization a porcelain body block or core 1, having at one end thereof a screw plug contact, 110

provided with socket terminals, while the other end thereof is provided with a lamp receptacle having suitable lamp terminals. The said body block 1 is preferably provided 5 with a central opening or bore 2 which extends throughout the length thereof, while one end is formed with an offset spacing flange or collar 3 having a wire receiving notch 4, and the opposite end 10 thereof is suitably finished as indicated at 5.

Carried by the end of the block 1, having the flange 3, is a screw contact plug which preferably comprises a porcelain plug body 6 having secured thereto a metallic coupling 15 ring 7 provided with a flange 8 for telescopically receiving the collar portion 3 of the porcelain body. Between the flange 8 and the periphery of the collar 3 is preferably provided a ring of insulation 9 which serves 20 to improve the fit between the porcelain body and the coupling ring, and to also protect the said ring from being short-circuited by contact with the wire which passes through the groove 4, and which will hereinafter be more fully referred to. The plug body 6 is further provided with a threaded shell member 10 for engaging with the screw shell contact of the socket, and is also provided with the center plug contact member 25 30 11, which is insulated from the screw shell by the block of insulation 12. The opposite end of the body block 1 has fitted thereto a screw shell contact member 13 which constitutes one of the terminals for an electric lamp, and as will be observed from the drawing this screw shell contact is held to the porcelain body 1 by means of a relatively long conductor screw 14, the same, however, not being in electrical contact with 35 the shell, but insulated therefrom by means of the insulating plate 15.

This conductor screw 14 performs the dual function of providing the center plug contact for the screw plug at one end of 40 the body and the center plug contact 16 for the lamp receptacle at the other end of the body, while at the same time holding all of the plug and lamp receptacle parts in their assembled relation. That is to say, the conductor screw 14 clamps the insulating cap 45 12 and plug body 6 against the flanged end of the porcelain body 1, and extends through the opening 2 of the latter to hold the screw shell contact 13 to the other end thereof 50 55 with the aid of the insulating plate 12.

Referring further to the plug body 6, it will be observed that the same preferably has an interior chamber A, which is in communication with a wire passage 6^a extending 60 at an angle through the side wall of the body, while the edge of the plug body is provided with a suitable wire receiving notch 6^b, which communicates with the notch 4 in the collar 3 to provide for receiving 65 the electrical connection 17 which

completes the circuit connections between the screw plug and lamp receptacle and constitutes a resistance in the lamp circuit. This electrical connection 17 is preferably a German silver wire of suitable gage having one end connected to the interior of the screw shell 10 of the plug portion of the device, and extending through the opening 6^a, chamber A, notch 6^b and notch 4 to the exterior of the hollow porcelain body block 1, where it is coiled thereabout, as shown in the drawings. It will of course be understood that this wire is not insulated, and is wound around the exterior of the body block 1 in the direction of the lamp receptacle, and is connected with the latter as indicated at 18. Accordingly, it will be apparent that the electric current, in passing through the device D, will follow the conductor 14, which forms the center contact of both the plug body and lamp receptacle, through the electric lamp to the screw shell contact 13 of the lamp receptacle, thence through portion 18 of the coiled wire 17, back to the screw shell portion 10 of the block.

In connection with the lamp receptacle portion of the device, it will be observed that in addition to the screw shell contact member 13, the same preferably includes an insulating sleeve 19, which serves to completely insulate the screw shell contact which constitutes one of the lamp terminals from a metallic casing member 20, which forms the entire exterior of the device and telescopes over the outer periphery of the metallic flange 8 of the coupling ring 7 carried by the plug body, thus providing a space between the exterior of the porcelain body block 1 and its interior surface, clearly shown in Figs. 3 and 4. As will be seen from Fig. 3, the metallic casing 20 carries a cord terminal 21 which is in metallic contact therewith, and also carries at a diametrically opposite point another cord terminal 22, which is insulated therefrom. That is to say, the cord terminal 22, while carried by the casing 20 is insulated therefrom by the washer 23 and bushing 23^a, and extends into metallic contact with the screw shell member 13 of the lamp receptacle. These cord terminals 21 and 22 are preferably in the form of projecting studs which are rigidly carried by the casing, thereby constituting a rigid point of contact for the coiled ends E of the applicator cords.

The said casing 20 which is spaced from the exterior of the core, as previously indicated, is electrically connected with the resistance coil 17 on the exterior of the body block, by means of a shiftable controller element 24. As will be seen from the drawings, the metallic casing 20 is provided with a longitudinally disposed milled slot or guideway 25 in which the shiftable con-

troller device slides to vary the amount of current supplied to the applicator cord terminals 21 and 22. This shiftable controller member 24 preferably comprises a 5 metallic shank portion 26, having its side portions notched to straddle the edges of the slot or guideway 25, and carries at one end a spring pressed contact ball 27, which establishes a metallic contact between the 10 casing 20 and the resistance coil 17, while the other end thereof is provided with an insulated button 28, which may be manipulated by the finger of the operator to change the position of the controller in the slot, and 15 thereby shift the ball 27 to different points along the resistance coil 17.

Referring now to Fig. 6, which shows a diagram of the electrical circuits, it will be apparent that the main circuit passes 20 through the center contact 11 of the plug assembly, thence through the conductor screw 14 to the center contact 16 of the lamp receptacle, thence through the filament F of the lamp L to the screw shell contact 13, 25 and from there through the wire 18 to the resistance coil 17, and thence to the screw shell member 10 of the plug. The shunt circuit passes from the screw shell contact member 13 to the cord terminal 22, and thence to 30 one of the cords C of the applicator circuit to one of the applicator handles or their equivalent, thence through the patient's body to the other applicator handle or its equivalent, and thence through the applicator cord 16 and cord terminal 21 to the metallic casing 20. From the metallic casing 20, the shunt circuit passes through the metallic shank 26 of the shiftable controller member to the ball 27 which slides over the 40 resistance coil 17.

Accordingly, it will be apparent that the present device provides for two complete circuits, namely, a lighting circuit, and a shunt vibrator circuit, which is utilized in 45 the treatment of the patient. It will of course be understood that the strength of the shunt circuit can be varied at will by moving the controller button 28 from one end of the slot to the other. Thus, there is provided a variable shunt circuit which is entirely within the control of the operator, according to the treatment required.

From the foregoing it is thought that the features and advantages of the invention 55 will be readily apparent, and it will of course be understood that changes in the form, proportion and minor details of construction may be resorted to without departing from the spirit of the invention or 60 scope of the appended claims.

We claim:

1. An electro-therapeutical device including an insulating body carrying at one end a receptacle element and at its opposite 65 end a plug element, a single tie screw con-

necting said several elements and forming the center plug contact therefor, a metallic casing, applicator cord terminals in circuit with the casing and receptacle element, a resistance in circuit with the receptacle element and having sufficient impedance to give a considerable voltage drop, and a contact element shiftable over said resistance and electrically connected with the metallic casing. 70

2. An electro-therapeutical device including an insulating body block, a screw shell receptacle arranged at one end of the block, a plug support arranged at the opposite end of the body, a plug contact arranged 80 on the plug support, a tie screw extending through the body block and having its opposite ends disposed respectively within the receptacle element and outside of the plug element to constitute the center plug contacts 85 for both of said elements, a metallic casing, applicator cord terminals respectively connected with the receptacle element and the metal casing, a conductor coiled about the insulating body block and having sufficient 90 resistance to give a considerable voltage drop, said conductor connecting with the screw shell and plug contacts of the device, and a shiftable contact element engaging 95 said casing and said resistance-conductor. 95

3. An electro-therapeutical device having socket terminals at one end, lamp terminals at the other end, an electrical connection therebetween including a conductor having sufficient resistance to give a considerable voltage drop, and means for tapping off a shunt circuit from the main circuit including a metallic casing, a shiftable contact between the resistance-conductor of the main circuit and the casing, and applicator 100 cord terminal posts carried by the casing, one of said posts being in electrical contact therewith, and the other insulated therefrom and electrically connected with one of the lamp terminals. 110

4. An electro-therapeutical device including an insulating body block, a main circuit including a screw plug contact at one end of said block, a lamp receptacle at the other end, a lamp therein, an electrical resistance-conductor between said plug contact and lamp receptacle adapted to give a considerable voltage drop, and a shunt circuit including a metallic casing member carried by the body block and insulated from the lamp receptacle, applicator cord terminals respectively carried by and in electrical contact with the casing and lamp receptacle, and a shiftable contact element between said resistance-conductor and the metallic casing 115 member for controlling the variation and voltage in said shunt circuit. 120

5. An electro-therapeutical device including an insulating body block, a main circuit including a screw plug at one end of 130

- said body block and having side and end contacts, a lamp receptacle at the other end and including a screw shell and a center contact, a lamp in said receptacle, a combined 5 conductor and tie element connected with the said center contact and the end contact of the plug, a resistance conductor carried by the insulating body block and having sufficient resistance to give a considerable 10 voltage drop and connected with the screw shell and side contact of the plug, and a shunt circuit including a metallic casing member carried by the insulating body block and insulated from said screw shell, and a 15 shiftable contact for electrically connecting the resistance-conductor and the metallic shell to control the variation of voltage in said shunt circuit.
6. An electro-therapeutical device including an insulating body block having a central opening, a screw plug carrying 20 socket terminals at one end of said body, a receptacle having lamp terminals at the other end of said body, a metallic part for

holding the plug and receptacle in assembled relation to the body and connecting the center terminals of both the plug and receptacle, a resistance coil wound around the exterior of said body and connecting the screw shell terminals of both the plug and 25 receptacle, a metallic casing surrounding the insulating body block and lamp receptacle and insulated from the latter, a cord terminal rigidly and electrically connected with the metallic casing, another cord terminal 30 carried by the casing but insulated therefrom and electrically connected with one of the lamp terminals, and a shiftable controller button for closing a shunt circuit between the resistance coil and metallic casing. 35 40

In testimony whereof we hereunto affix our signatures in the presence of two witnesses.
